PACKING CASE

George W. Boh, Chattanooga, Tenn.

Application July 16, 1936, Serial No. 96,827

5. Claims. (Cl. 229—23)

This invention relates to packing cases and more particularly to an improved case or crate for packing, shipping and storing fruits and vegetables.

According to the present invention, the case is formed from one or more blanks of relatively stiff, strong and tough paperboard or fibreboard material, comprising end wall panels, front and rear wall panels and top and bottom panels forming the bottom and the cover of the case respectively. The end wall panels may be provided with relatively rigid reinforcing frames of wood or metal. The top and bottom panels may be hingedly connected to the opposite side wall panels and cooperate with the end frame and end wall panels when closed to provide a rigid structure. One or more reinforcing cleats may be attached to the side wall panels to give additional longitudinal rigidity to the case.

The side wall panels are preferably connected to the end wall panels in such a manner that the packing case may be collapsed in a relatively flat condition for shipment and storage. A considerable saving in shipping and storage costs is thus effected. When fruits or vegetables are to be packed in the case, the packer erects the end wall panels and the front and rear side wall panels into rectangular form. The top panel is then swung into closed position and the case inverted so that the top panel rests upon a suitable supporting platform with the end wall panels and front and rear side wall panels resting upon the top wall panel. A layer of selected fruit or vegetables is then carefully packed within the case so as to rest upon the inside face of the top wall panel, following which the remainder of the fruits or vegetables may be dumped or poured into the case so as to fill the same. When the case has thus been filled the bottom panel is swung into closed position and is permanently secured in closed position by means of suitable securing means, such as nails, screws, staples, or the like. When the bottom panel has been firmly secured in position, the case with the fruit or vegetables packed therein is then re-inverted so that the contents will rest upon and be supported by the bottom panel. The cover panel can then be lifted and the top layer of fruit or vegetables given a final inspection, following which the cover panel is secured in closed position.

The improved packing case herein disclosed can be inexpensively manufactured and assembled. The completed case is light in weight and yet strong and rigid and provides ample support and protection for the contents. The in-

terior faces of the paperboard end, side, bottom and top panels are smooth and even, and the packing case can be used without liners, guards, or other means to protect the contents against abrasion or injury from contact with the walls of the case, as is necessary where wooden packing boxes or crates are used. My improved packing case is admirably adapted as a packing medium for delicate fruit and vegetables such as peaches, tomatoes, apples, and citrus fruits, which may be easily injured and damaged during packing, shipment or storage.

The paperboard or fibreboard forming the packing case may be suitably treated with a filler and waterproofing material before assembly, so as to resist moisture which might otherwise weaken the case or injure the contents. The reinforcing cleats associated with the end wall and side wall panels may be so constructed as to raise the paperboard material out of contact with wet or damp floors and to permit the free circulation of air between and around the stacked packing cases. The reinforcing cleats also provide skids which permit the case to be pushed along the floors of the packing house or transporting conveyances without injury to the case. If desired, the side and end wall panels may be provided with suitable spaced openings to permit the free circulation of air through the walls.

Various other features and advantages of the invention will be apparent from the following particular description and from an inspection of the accompanying drawings.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawings forming a part thereof, in which:

Fig. 1 is a plan view of a blank suitable for forming a packing case in accordance with the invention;

Fig. 2 is an enlarged fragmentary cross-sectional view of the blank showing the formation of the scoring of the blank, this view being taken along line 2—2 of Fig. 1;

Fig. 3 is a perspective view of the blank used in forming the end wall panel of the container;

Fig. 4 is an exploded perspective view showing a partially formed packing case with one of the side wall panels attached to the end wall panel

and the other side wall panel in position to be assembled with the end walls;

Fig. 5 is a fragmentary perspective view showing the packing case set up and the contents assembled therein;

Fig. 6 is a transverse cross-sectional view of the case being packed while in mounted position;

Fig. 7 is a perspective view showing the packing case completely packed and closed;

Fig. 8 is an enlarged fragmentary view of the corner of the packing case showing a modified constructional detail;

Fig. 9 is a fragmentary perspective view of a modified form of container adapted to be collapsed for shipment;

Fig. 10 is a perspective view of the container shown in Fig. 9 in partially folded condition; and

Fig. 11 is a plan view of a blank suitable for forming the container shown in Figs. 9 and 10.

Referring now particularly to Fig. 4 there is shown a partially assembled packing case including a plurality of blanks 1, 2 having panels adapted to form side walls, covers and end walls. Preferably the blanks 1 are similar but reversely and inversely positioned.

Referring to Fig. 1 the blank 1 may be formed from suitable sheet material such as fibreboard, paperboard or other similar material of sufficient rigidity to be shape-sustaining but which may be made flexible in a convenient manner as by scoring. The blank 1 is divided by a score line 7 into a side wall panel 5 and a cover panel 6. Extending from the ends of the side wall panel 5 are side wall flaps 8 which are bendable about score lines 9. Extending from end walls of the cover panel 6 are cover flaps 10 which are bendable about score lines 11, preferably aligned with score lines 9. Extending from the free edge of the cover panel 6 is a side cover flap 12 bendable about a score line 13. Cover tabs 14 extend from the ends of the side cover flap 12 and are bendable about score lines 15 preferably aligned with score lines 9 and 11.

The score lines may be formed in various ways in order to provide lines of increased flexibility, or if desired, other ways of obtaining lines of increased flexibility may be substituted. Preferably the various score lines are formed as shown more in detail in Fig. 2. For example, the score line 7 includes angular portions 16 and 17 and the offset portion 18 displaced from the plane of the adjacent material. This type of scoring permits repeated bending of the blank along the score line 7 without destroying or unduly weakening the material, and also serves to reinforce and stiffen the edge formed when the adjacent portions of the blank are bent in angular relation about the score line.

Where it is desired to provide ventilation for the packing case, as for example, where it is to be used for packing fruits, vegetables or other perishable commodities, suitably spaced and shaped perforations 20 may be provided in suitable portions 65 of the blank. In the present instance the perforations 20 are formed in the side wall panel of the blank.

The end walls 2 preferably are similarly formed and each includes a rectangular panel 25 of sheet material which may be formed of the same material as that used in forming the blank 1.

The panel 25 is suitably secured to an end frame which may be formed from a plurality of cleats 26 suitably secured at their ends as by a rabbed joint 27. The cleats 26 may be of any

suitably rigid material and preferably are formed of wood. The panel 25 may be suitably secured to the end frame as by staples 28 or other fastening members.

The packing case may be assembled by attaching the side wall end flaps 8 to the vertical cleats 26 of the end frames respectively, one of the blanks 1 being attached so that the hingedly attached cover panel 6 is adapted to overlie the top edges of the end walls 2, and the other of the blanks 1 being attached to the opposite other vertical cleats 26 so that the corresponding hingedly attached cover panel 6 cooperates with the lower horizontal cleats 26 and lower edge of the first side wall panel 6.

Where the packing case is to be employed in packaging articles such as fruit, vegetables or the like, it is generally desirable to reinforce the case longitudinally in order to make it sufficiently rigid to withstand the shocks incident to handling and shipping and to prevent the side walls from bowing and thereby preventing displacement of or damage to the contents. The side walls preferably are reinforced by longitudinal cleat 34 secured to the free edge of each side wall panel 5 and a second longitudinal cleat 35 secured to the edge of the side wall panel adjacent the score line 7. The cleats 34 and 35 preferably are secured to the side wall panels 6, as by stapling (not shown) or any other suitable manner and also may be secured to the end frames as by nails 36, screws or the like, thereby to provide a rigid, reinforced case.

Preferably the cover flanges 10 and 12 are bent about the score lines 11 and 13 respectively and the tongues 14 bent about the score lines 15 and secured to the cover panel end flanges 10 in a suitable manner as by staples 30. This provides a continuous, upstanding flange extending around the free edges of the cover which, when the cover is in closed position telescopes over the adjacent edges of the side and end walls and serves to retain the cover in proper position. The flange also serves as a convenient means for permanently fastening the cover in closed position.

The packing case may be packed as follows: The top cover 1 is closed and the case is inverted and disposed on a suitable supporting surface, the side and end walls resting upon the top cover 1. The contents may be disposed in the case in any desired manner, but preferably the lowermost layer is disposed neatly and evenly in predetermined planar arrangement on the inner face of the top cover 1 (lower cover in Fig. 7). The succeeding layers may be either arranged in a predetermined manner or dumped or poured in on top of the first layer. After the case has been completely filled, the bottom cover 6 (upper cover in Fig. 7) is closed and may be secured in position by suitable fastening means such as nails 37, screws, staples or the like. The case is then inverted and the top cover 1, which then becomes the upper cover, may be raised in order to inspect the contents to ascertain if the top layer is arranged in the desired manner. Also, any of the articles of the top layer which may be damaged or which are unattractive in appearance may be removed and replaced. The case may then be completely closed by securing the top cover 1 as by nails, screws or the like.

If desired, the free edge of the side wall panel 6 may be formed with a score or bead 21 in order to cushion the contents adjacent the edge of the side wall and prevent crushing or bruising of the contents. In any event it is preferable that

the top and bottom edges of the side wall panels extend to a point flush with or higher than the edges of the cleats 34 and 35 and the top and bottom edges of the end wall blanks 25 extending beyond the corresponding edges of the cleats 26. This prevents the contents from being bruised by the edges of the cleats during packing.

Further protection to the contents may be provided by forming the end wall panels 25 with integral extensions 40 adapted to extend across the edge and face of each horizontal end cleat 26. The end wall panel 25 may be secured to the cleat by staples 42 extending through the extension 40 and cleat 26 from the outside of the case. In an analogous manner the side wall panel may have an extension 43 adapted to pass over the edge and faces of each cleat 34 and to be secured thereto by staples 45 passing through the extension 43 and the cleat 34 from the outside. By this construction not only are the sharp corners of the cleats covered, but in addition, the staples or other securing members which may be used do not project through the inner wall surfaces of the case and the inside wall surfaces therefore are completely smooth.

Referring now to Figs. 9 and 10 there is shown a slightly modified packing case, which is constructed generally along the lines of the case thus far described but which is adapted to be folded into collapsed condition for convenient shipment to the place where it is to be packed. The packing case shown in Figs. 9 and 10 preferably includes a plurality of blanks 101 each having a side wall panel 105 with side wall end flanges 108 extending therefrom and bendable about score lines 109. Integrally and flexibly attached to side wall panel 105 along a score line 107 is a cover panel 106 having end flanges 110 bendable about score lines 111 and a side flange 112 bendable about score line 113.

The end walls 102 include blanks 125, forming end wall panels and secured to end frames formed by suitably connected cleats 126.

The blanks 101 are secured as by staples 129 to the vertical cleats 126 of the end frames in the manner above described thereby to form a substantially tubular structure including the side walls and end walls. The covers are integrally and flexibly attached to opposite edges of the side wall panels, as described in connection with the packing case shown in Fig. 5.

A cleat 134 is attached to the free edge of each side wall panel 105, as by staples 136 and a cleat 135 is attached adjacent the score line 103 as by staples 136. The cleats 134 and 135 preferably extend across the edges of the end frames, however, the cleats 134 and 135 are unconnected to the side wall panel 105 over a zone 151 which is slightly greater in width than the thickness of the adjacent end frame. The zone 151 is defined by a score line 109 and by a second score line 150 which permits the side wall panel 105 to bend around the end of the end frame when the packing case is collapsed. Since the cleats 134 and 135 are not connected to the side wall panel 105 over the zone 151, the zone can be bent away from the cleats. The cover panel 106 is provided with a slot 153 extending inwardly from the end edge to a point adjacent the score line 150 thus permitting the zone 151 to move away from the cover panel for the folding movement. The other side wall panel 106 is similarly formed with a zone 151 and score line 150 at the opposite end of the packing case and the other

cleats 134 and 135 are likewise unconnected over this zone.

The packing case may be folded by forcing the side walls laterally toward each other so that the end walls bend about the score lines 152, zone 151 bending around the vertical edges of the end walls. The end walls bend inwardly about score lines 109 and permit the tubular portion of the case to be collapsed, the covers extending laterally from the collapsed portion. However, if it is desired to fold the case into a more compact form, each cover panel 106 may be provided with a score line 154 parallel to and spaced from the score line 107 a distance approximately equal to the thickness of the cleat 135. This permits the cover panel 106 to be folded backwardly over the cleat 135 and to lie across the cleats 135 and 134 in proximity to the side wall panel 105.

It will be noted that the side walls, end walls and covers are constituted principally by paper-board, fibre-board or like material hence the case is relatively economical to construct and may be made relatively light in weight. Furthermore the inner walls are smooth and there is no likelihood of the contents being cut or bruised when in the case. It is therefore unnecessary to provide any additional protective members such as a liner, guard or the like.

The blanks may be formed of various suitable material and if desired this material may be relatively soft and resilient and thus provide a cushioning effect for the contents. Preferably the blanks are of single ply material, but in certain instances they may be formed from laminations certain of which may be relatively hard 35 and stiff to provide sufficient rigidity and others which may be relatively soft and resilient to cushion the contents.

The blanks may be suitably waterproofed as by the application of a suitable coating or filler 40 and thereby provide a substantially moisture-proof case which will prevent the contents from being wet by the entrance of moisture from the outside and also which will prevent wetting of other cases or containers in the event that the 45 contents in one of the cases should become crushed or damaged. The case may be disposed on its side and the longitudinal cleats support the paperboard wall out of contact with any moisture which may be on the floor of the building or vehicle in which the case is located.

While certain novel features of the invention have been disclosed and are pointed out in the annexed claims, it will be understood that various omissions, substitutions and changes may be 55 made by those skilled in the art without departing from the spirit of the invention.

I claim as my invention:

1. A foldable packing case including side and end walls formed of paperboard material and 60 flexibly joined at adjacent edges to permit said walls to be folded, rigid frames reinforcing said end walls, reinforcing cleats extending along said side walls, and means attaching said reinforcing cleats to said side walls, said cleats being unconnected to said side walls over an end zone approximately equal to the thickness of the end frames to permit said zones to be bent out of the plane of said side walls, when said walled structure is folded.

2. A foldable packing case including side and end walls formed of paperboard material and flexibly joined at adjacent edges to form a tubular structure and to permit said walls to be folded, rigid frames reinforcing said end walls, 75

reinforcing cleats extending along said side walls and across the edges of said end walls, and means attaching said reinforcing cleats to said side walls, said cleats being unconnected to said side walls over an end zone approximately equal to the thickness of the end frames to permit said zones to be bent out of the plane of said side walls, when said tubular structure is folded.

3. A packing case for fruits and vegetables including relatively rigid end walls, side wall panels extending between said end walls, flaps extending from the ends of said side wall panels, means attaching said flaps to the outer faces of said end walls, vertical fold lines at the junctions of said side walls and said flaps and substantially within the planes of the outer faces of said end walls when said packing case is set up, thereby permitting said side and end walls to be folded into flat condition, and a vertical fold line extending along each of said side walls, parallel to one of said first named score lines and spaced therefrom a distance approximately equal to the width of the adjacent end wall for permitting said side wall material to bend around the vertical edge of said side wall when said walls are folded.

4. A packing case for fruits and vegetables including relatively rigid end walls, side walls extending between and hingedly connected to said end walls, vertical fold lines extending along said side walls substantially within the plane of the outer faces of said end walls, when said packing

case is set up thereby permitting said walls to be folded, a vertical fold line extending along each of said side walls parallel to one of said first named fold lines and spaced therefrom a distance approximately equal to the width of the adjacent end wall to define a vertical panel for permitting said side wall material to bend around the vertical edge of said side wall, reinforcing members extending along said side walls, and across the edges of said end walls, and means attaching said reinforcing members to said side walls, except at said vertical panel.

5. A blank for forming a folding packing case comprising a side wall panel, a cover panel integrally and flexibly connected to a side edge of said side wall panel along a fold line, an end flap integrally and flexibly connected to an end edge of said side wall panel along a second fold line aligned with the corresponding end edge of said cover panel, a third fold line in said side wall panel extending parallel to said second-named fold line from said first-named fold line to the opposite side edge of said side wall panel and a slot extending from the juncture of said first and third fold lines to the adjacent end edge of said side wall panel, said slot permitting the section of said side wall panel between said second and third named fold lines to be bent out of the plane of the remainder of the side wall panel.
